(57) **CLAIM**

The ornamental design of a canopy fixture for pendant light, as shown and described.

DESCRIPTION

FIG. 1 is a top view of a canopy fixture for pendant light; FIG. 2 is a bottom view of the canopy fixture for pendant light of FIG. 1;

FIG. 3 is a first side view of the canopy fixture for pendant light of FIG. 1;

FIG. 4 is a second side view of the canopy fixture for pendant light of FIG. 1;

FIG. 5 is a top perspective view of the canopy fixture for pendant light of FIG. 1;

FIG. 6 is a side perspective view of the canopy fixture for pendant light of FIG. 1 with a pendant light removably positioned within said canopy fixture;

FIG. 7 is a bottom perspective view of the canopy fixture for pendant light of FIG. 1; and,

FIG. 8 is a bottom perspective view of the canopy fixture for pendant light of FIG. 1 with a pendant light removably positioned within said canopy fixture for pendant light.

The broken lines shown in the drawings are for environmental purposes only and form no part of the claimed design.
